UNITED STATES PATENT OFFICE.

WILLIAM P. FOLEY AND RALPH W. KNUPP, OF SOMERSET, PENNSYLVANIA.

GATE.

Application filed June 7, 1921. Serial No. 475,846.

To all whom it may concern:

Be it known that we, WILLIAM P. FOLEY and RALPH W. KNUPP, citizens of the United States, residing at Somerset, in the county of Somerset and State of Pennsylvania, have invented certain new and useful Improvements in Gates, of which the following is a specification.

This invention relates to automatic gate operating mechanisms and more particularly to that class of vertically operated gates operatively connected to an elevator or lift such as is used in mine hoist shafts or other elevator shafts.

The primary object of the invention is to provide an automatically operated gate or gates at the entrance to an elevator shaft so that the same must be brought to its closed position before the lift or cage can leave its landing point thus preventing the possibility of any one falling down the shaft when the cage or lift is not at the landing.

Another object of the invention is to provide a pneumatically operated, safety gate cooperating with a lift or cage in such manner that the open or closed position of the gate is at all times controlled by the position of the cage with respect to a landing point.

A continued object of the invention resides in the construction of a simple, yet highly efficient pneumatically operated device for automatically raising or lowering a gate or gates, and one in which the relative position of the parts are so arranged as to permit of easy installation in any mine shaft at a minimum of expense and without considerable labor.

With these objects in view, the invention consists of the construction and novel combination and arrangement of parts herein-after fully described, illustrated in the accompanying drawings and pointed out in the subject matter being claimed, it being understood that various changes in the form, proportion, size and minor details of construction may be resorted to without departing from the spirit and scope of the invention or sacrificing any of the advantages thereof.

With these objects in view and others which will be manifest and suggested as the purpose and nature of my invention are revealed in the following specification and

drawing wherein we have shown a practice, yet preferred embodiment thereof, 55

Figure 1 is a side elevation showing the cage in dotted lines and the operating mechanism for the gate.

Fig. 2 is a detail sectional view of the air or steam ram for operating the gate. 60

Fig. 3 is a sectional view of the brake cylinder used in connection with the operating mechanism.

Figs. 3^a and 4 are sectional views showing the control valve in its different positions. 65

Figs. 5 and 6 are vertical sectional views of the same, and

Fig. 7 is a perspective of a trip disk for operating a spring pushed control valve. 70

Referring now to the drawings wherein like numerals designate corresponding parts throughout the several views, 5 designates the vertically slideable gate which is provided at its top and bottom with extended eyes 6, 7, arranged to act as guides for the said gate operable between the vertical side guide rods 8, 9, extending from the flooring to a suitable beam, for instance, as clearly shown by Fig. 1. The gate, of course, constitutes the closure for the cage or lift 10 shown in dotted lines, operable in the shaft by means of the hoist rope 11 connected to the hoisting drum 12 of the structure. 75

A gate elevating element, in the form of 85 a cable or rope 13, is connected as at 14, to the top of the gate 5, and which passes over a pair of pulleys 15, 16, arranged on the top of a beam 17. The element 13, depends from the pulley 16, and is secured as at 18^a, 90 to the outer end of a piston rod 17^a, the latter having its inner end provided with a piston 18, operable within a vertically disposed cylinder 19, which is offset somewhat with respect to the guide rod 8, 9, and is 95 formed at its upper end with a tubular inlet and exhaust, as indicated at 19^a, and at its lower end with a combined inlet and exhaust, as indicated at 19^b.

Arranged within the cylinder 19, at the bottom thereof, is a coiled spring 20, which acts as a cushion for the piston 18, when the latter is in its lowest position. 100

A compressed air or steam conducting pipe 20^a, has one end thereof connected to the combined inlet and exhaust 19^a, and has 105

its other end connected to a controlling valve mechanism. The compressed air or steam conducting pipe 23, has one end connected to the combined inlet and exhaust 19^b, and its other end connected with the controlling valve mechanism.

The controlling valve mechanism comprises a cylindrical casing 50, having a closure cap 51, threadably engaging with the upper end of the said casing, and said cap 51, is formed with a centrally disposed opening 52. The casing 51, at one side has a pair of superposed lateral nipples 53, 54, at the opposite side it has a lateral nipple 55, and its bottom formed with a depending nipple 56. The nipples 53, 54, 55 and 56, register with openings 57, 58, 59, 60, respectively.

Arranged within the casing 50, is a cylindrical valve 21, which snugly fits, but can be shifted within the casing 50, and the valve 21, at its upper end, is provided with an extension 61, which projects through the opening 52, and is attached to an actuating handle 26.

The valve 21, is formed with a centrally disposed vertically extending passage 46, opening at its lower end at the bottom of the valve 21, and permanently registering with the opening 60. The passage 46, at its upper end terminates in a radially disposed port 47, which opens at the periphery of the valve 21. Communicating with the passage 46, below the port 47, is a radially disposed port 48, which also opens at the periphery of the valve 21. A semi-circular passage 45, is formed in the periphery of the valve 21, and the latter is formed with a peripheral passage 49, which depends from the passage 45, and which has its lower end terminating at one side of the outer end of the port 48. The port 49, opens into the passage 45, intermediate the ends of the latter, and the passage 45, permanently communicates with the opening 59, and when the valve 21, is shifted the passage 45 is positioned to communicate with the opening 57, as clearly shown in Figure 5. When the valve 21, is shifted to the position shown in Figure 6, the port 48 communicates with the opening 54, and when the valve 21, is shifted to the position shown in Figure 4, the port 47 registers with the opening 57 and the port 49 registers with the opening 58.

The conducting pipe 20^a, is attached to the nipple 55, the conducting pipe 25 is connected to the nipple 56, and attached to the nipple 53, is a supply pipe 44, and connected to the nipple 54, is an exhaust pipe 43.

When the valve 21, is shifted to the position shown in Figure 3^a, the passage 45 communicates with the pipes 44 and 20, and the port 48, establishes communication be-

tween the pipe 43 and the passage 46. When the valve 21, is shifted to the position shown in Figure 4, the passage 45 communicates with the pipe 43, through the medium of the passage 49, and the passage 46, communicates with the pipe 44, through the medium of the port 47. When the valve 21 is shifted to the position shown in Figure 3^a, a supply of pressure is had to the pipe 20^a, and exhaust is had from the pipe 25, and when the valve 21, is shifted to the position shown in Figure 4, a supply is had through the pipe 25, and an exhaust is caused through the pipe 20^a.

Interposed in the conducting pipe 20^a, is a spring controlled valve 22, which is normally in closed position and the function of which is to control supply and exhaust from the upper end of the cylinder 19. The valve 22 is intermittently operated and the manner in which it is operated will be presently referred to. The valve 22, controls the supply of pressure against the piston 18, to prevent the elevating or lifting of the gate 5, until the elevator or lift 10 arrives at a landing and which will be hereinafter referred to.

The hoisting drum 12, has associated therewith, a brake band 12^a, formed with a pair of lugs 28, to the former is pivotally connected a link 29, as at 29^a, and to the latter is pivotally connected as at 30^a a link 30. The link 29, is pivotally connected to the link 30, as at 30^b. The link 30 is pivotally connected as at 31^a, to a piston rod 31, which carries a piston 32, arranged in a brake cylinder 33.

Extending from the pipe 20^a, and opening into the cylinder 33, rearwardly of the piston 32, is a conducting pipe 34, and opening into the cylinder 33, forwardly of the piston 32, is a conducting pipe 35, which communicates with the pipe 23. By this arrangement the control of the brake cylinder is had through the medium of the controlling valve mechanism.

The hoisting drum shaft is indicated at 37, and which has one end provided with a small sprocket 38, operatively connected with a larger sprocket 39, by an endless belt 40. The sprocket 39, is mounted on the shaft 39^a, provided with a bevelled pinion 39^b, which meshes with a bevelled pinion 39^c, carried on the lower end of a vertically disposed shaft 40^a. Mounted on a shaft 41^a, is a disk 41, which is formed with a lug 42, engageable with the stem 42^a, of the valve 22, for the purpose of opening the latter, so that a supply of pressure can be had through the pipe 20^a for the purpose of lowering the piston 18 for shifting the element 13, thereby elevating the gate 5. The shaft 41^a has a bevelled pinion 42^b, which is in mesh with a bevelled pinion 42^c, carried on the upper end of the shaft 40^a.

The disk 41, is geared to the sprocket 39

and shaft 37, so that the rotary movement of the disk will not exceed one complete revolution for the travel of the cage from one landing to another, and by this arrangement when the cage 10, reaches a landing, the lug 42 will operate the stem 42^a, thereby opening the valve 22, and permitting of supply and exhaust to and from the cylinder 19 through the pipe 20^a.

10 During the travel of the elevator or lift from landing to landing, the brake 12^a, is in an inoperative position, due to the fact that the controlling valve mechanism is so positioned that the pressure is exhausted 15 through pipes 34 and 20^a, and when the elevator or lift reaches the landing and pressure is supplied to the pipe 20^a through the operation of the valve mechanism, pressure will also be supplied to the cylinder 20^a, causing the operation of the piston 32, and the brake 12^a and in this connection exhaust is had from the cylinder 33, through the pipes 35 and 23, and by this arrangement 25 the application of brake 12^a, is had on the drum, until it is time for the elevator or lift to leave the landing, but before the application of the brake is removed, controlling valve mechanism is operated, so as to supply pressure to the cylinder 33, 30 through the pipes 23 and 35, and this also causes the supply of pressure to the cylinder 19, below the piston 18, at the same time an exhaust of pressure is had through the pipes 20^a and 34, and on the supply of pressure in 35 the manner as stated the brake 12^a is released and the piston 18 moved upwardly and the gate 5 will move to closed position by gravity.

40 When the valve 21, is shifted to the position shown in Figure 3^a, a supply of pressure is had to the pipes 20^a and 34, and exhaust is had through the pipes 23 and 35, and when the valve mechanism is shifted to 45 the position in Figure 4, a supply of pressure is had to the pipes 23 and 35, and exhaust through the pipes 20^a and 34. The valve 22, is always closed unless it is released through the medium of the disk 41, and 50 lug 42.

If the cage is positioned intermediate a pair of landings, the brake 12^a can be applied without in any manner effecting the position of the gate 5, due to the fact that the valve 55 22, is closed.

In the accompanying drawings, we have 60 illustrated our invention embodied in one form by way of example, and which in practice has been found to be highly satisfactory in obtaining the desired results. It will be obvious however that other embodiments may be adopted and that various changes in the details of construction may be resorted to by those skilled in the art 65 without departing from the spirit and scope

of the invention. It is furthermore understood that the invention is not necessarily limited or restricted to the precise elements shown except insofar as such limitations are specified in the subject matter being claimed.

Having shown and described our invention, what we claim as new and desire to secure by Letters Patent of the U. S. is:—

1. A device for the purpose set forth comprising an elevator shaft gate lifting member normally in inoperative position and shifted to such position by the weight of the gate, a cylinder provided with a pressure operated piston connected to said member, conducting pipes opening into said cylinder above and below said piston and each providing for supply and exhaust, a releasable valvular element mounted in one of said pipes for arresting the operation of said piston when the elevator is between landings to prevent the shifting of said member from inoperative position, a valve mechanism for controlling supply and exhaust through said pipes, and means operated from the hoisting mechanism of the elevator when the latter reaches the landing for releasing said valvular element whereby on the operation of said valve mechanism to one position said piston will be shifted to move said member to operative position.

2. A device for the purpose set forth comprising an elevator shaft gate lifting member normally in inoperative position and shifted to such position by the weight of the gate, a cylinder provided with a pressure operated piston connected to said member, conducting pipes opening into said cylinder above and below said piston and each providing for supply and exhaust, a releasable valvular element mounted in one of said pipes for arresting the operation of said piston when the elevator is between landings to prevent the shifting of said member from inoperative position, a valve mechanism for controlling supply and exhaust through said pipes, means operated from the hoisting mechanism of the elevator when the latter reaches the landing for releasing said valvular element whereby on the operation of said valve mechanism to one position said piston will be shifted to move said member to operative position.

3. A device for the purpose set forth comprising an elevator shaft gate lifting member normally in inoperative position and

shifted to such position by the weight of the gate, a cylinder provided with a pressure operated piston connected to said member, conducting pipes opening into said cylinder above and below said piston and each providing for supply and exhaust, a releasable valvular element mounted in one of said pipes for arresting the operation of said piston when the elevator is between landings 10 to prevent the shifting of said member from inoperative position, a valve mechanism for controlling supply and exhaust through said pipes, means operated from the hoisting mechanism of the elevator when the latter reaches the landing for releasing said valvular element whereby on the operation of 40 said valve mechanism to one position said piston will be shifted to move said member to operative position, and means for cushioning the movement of the piston when said member is shifted to operative position.

4. A device for the purpose set forth comprising an elevator shaft gate lifting member normally in inoperative position and shifted to such position by the weight of the gate, a cylinder provided with a pressure operated piston connected to said member, conducting pipes opening into said cylinder above and below said piston and each providing for supply and exhaust, a releasable

valvular element mounted in one of said pipes for arresting the operation of said piston when the elevator is between landings to prevent the shifting of said member from inoperative position, a valve mechanism for controlling supply and exhaust through said pipes, means operated from the hoisting mechanism of the elevator when the latter reaches the landing for releasing said valvular element whereby on the operation of 40 said valve mechanism to one position said piston will be shifted to move said member to operative position, a brake element associated with said mechanism and applied thereto simultaneously with the shifting of said member to operative position, a fluid pressure operated means communicating with said pipe and connected to said brake element for operating the latter when said member is shifted to operative position, means for releasing said brake element simultaneously with the shifting of said member to inoperative position by the gate, and means for cushioning the movement of the piston when said member is shifted to 50 operative position.

In testimony whereof, we affix our signatures hereto.

WILLIAM P. FOLEY.
RALPH W. KNUPP.
